UNITED STATES PATENT OFFICE.

CHARLES HARRY ROECKNER, OF HAMBURG, GERMANY.

REVOLVING DOOR.

No. 858,028.

Specification of Letters Patent.

Patented June 25, 1907.

Application filed November 23, 1905. Serial No. 288,788.

To all whom it may concern:

Be it known that I, CHARLES HARRY ROECKNER, a subject of the King of Great Britain, and a resident of Hamburg, in the 5 German Empire, have invented a certain new and useful Improvement in Revolving Doors, of which the following is a specification.

The present invention relates to a revolving door, consisting of four wings which when in use revolve together about a central axis.

The object of the invention is to construct a door of this description on which in case of danger the people rushing out move the parts or wings of the door to a side, in such manner that all four wings swing outward and allow a free passage. For this purpose the wings of the door are operatively connected with 15 one another by special moving-mechanisms in such manner that the inner wings set the outer ones in motion to turn them outwardly.

In the drawing a door is shown made according to this invention.

Figure 1 shows a sectional elevation of the door, drawn to the line 1—1 of Fig. 2 and Fig. 2 shows a plan several parts broken away and others omitted for sake of clearness. Fig. 3 is a sectional elevation of a detail showing a coupling mechanism for coupling the moving mechanism to the wing of the door and Fig. 4 is a sectional plan of the same. Fig. 5 is a sectional elevation of a 30 modification of the coupling mechanism and Fig. 6 a horizontal section of the same. Fig. 7 is a vertical section of a detail showing a locking mechanism to connect the wings with each other at the center of the door and Fig. 40 8 is a horizontal section of the same drawn to the line 8—8 of Fig. 7.

In the mode of construction shown in the drawings the moving mechanism consists of a system of arms and links connecting the four wings *a b c d* in certain positions in a special manner. On each wing there is attached a hollow shaft or on top and bottom a socket *e* and *e'*, which may turn about a vertical rod *f*. At their lower ends the four rods *f* are fastened to 45 a circular ring *g*, which turns below the floor about the central axis of the door together with the latter, when in normal use. The upper sockets *e* as well as the rods *f* are prolonged above the top of the wings of the door 50 and are surrounded by strong rings or bosses

having arms, which for sake of clearness in the drawings are referred to not only by the numbers 5 and 6 but also by the letters of the corresponding doorwings as indexes. Thus the arms 5 and 6 of the wing *a* are called 5^a 6^a and 6^b, those belonging to the wing *b* are called 5^b and 6^b and so on. The arm 5 of each wing is connected with the arm 6 of the next following wing by a link 7 as may be clearly seen in Figs. 1 and 2. Above the arms 5 and 6 there are two more bosses also provided with arms *k*¹ and *k*², each arm *k*¹ having a longitudinal slot *t*, into which projects a stud *s* attached to the arm *k*² of the preceding doorwing. 70

There is a coupling mechanism in connection with every one of the bosses, with the exception of the boss of the arm 5 which is provided with two coupling-mechanisms for a purpose stated farther on. This coupling mechanism Fig. 3 and 4 consists of a divided coupling piece *m n* arranged to slide within a casing *l* attached to each boss of the aforesaid arms. The two parts *m* and *n* are held asunder by springs *v* and the part *n* is acted 80 upon by springs *v*¹ resting in the wall of the casing *l*, so as to tend to withdraw the coupling piece out of engagement of a slot *e*² of the socket *e*. To allow this disengagement to take place with greater ease the part *m* is 85 somewhat wedge-shaped. The part *n* is provided with an anti-friction roller *u*, which on mounting a segmental rib mentioned farther on pushes the coupling piece inwardly so as to force the wedge-shape part *m* into 90 the correspondingly shaped slot *e*² and coupling the boss carrying such coupling piece with the socket *e*.

Between the bosses of the lowest arms 5 and the wings of the door there is a circular 95 frame *h*, through which the upper sockets *e* project and which together, with the rods *f* and the lower ring *g* form a revolving cage, on which the wings *a, b, c, d* may swing about the rods *f* when unlocked. The rods *f* on the 100 upper ends are attached to strong beams 2 which are connected to a strong central pin 1 rotatively suspended on a ball-bearing 4, arranged on beams 3, which are supported at their ends directly on the wall or on a casting *o* resting on the wall. The casting *o* which is made circular is provided with segmental ribs *w*^a, *w*^b, *w*^c, *w*^d, *w*¹ and *w*², which each extend over one quarter of a circle and on which the rollers *u* of the coupling pieces 110

described above roll when passing them on the rotation of the door, so as to couple the arm in connection with such coupling piece with the socket e carrying the same. The 5 ribs are positioned in such manner that in the position of the door shown in Fig. 1 and 2 the four wings are in line with the centers of the ribs; rib w^a lying opposite the lower coupling-piece of the arm 5^a and w^1 opposite the coupling piece of the arm k^1 belonging to the door wing a , rib w^b opposite the coupling piece of the arm 6^b belonging to the wing b , w^c opposite the upper coupling piece of 5^c , belonging to c , w^d opposite the coupling piece of 6^d , and w^2 opposite the coupling piece of k^2 belonging to the door wing d . In this way in the position shown the arm 5^a and the arm k^1 are coupled to the socket e of the wing a and thus with the wing 20 a , the arm 6^b is coupled to the wing b , the arm 5^c with the wing c , and the arm 6^d and k^2 of the wing d are coupled to the wing d . All other arms in this position of the door 25 are not coupled to the socket carrying them. Thus when in case of fire or other danger, the people rush against the door, when in position shown in the drawing, the wings a and d turn about their rods f outwardly in the direction of the arrows. The 30 arms 5^a and 6^d coupled to these wings transmit the rotation to the arms 6^b and 5^c by means of the links 7, thus also forcing the wings b and c to rotate in the direction shown.

In order to prevent the door-wings b and c 35 from hindering each other in this moving, provisions are made to hold one of these two wings for instance c back until the other is rotated to such an angle, that no hindrance takes place. This is done by giving the 40 coupling, which connects the arm 5^c to the wing c , a certain amount of play and by arranging the arms k^1 and k^2 on the wings a and d , which force these wings a and d to start together. There being no play in that coupling, which connects the arm 6^b with the wing b , the latter will also move together 45 with the wings a and d , while the play in the coupling connecting the arm 5^c will allow the wing c to remain at rest until the wing b has 50 cleared its way, whereupon it will follow the wing b and also turn outwardly. When the wings a and d are turned outwardly to an angle of about 90° , standing nearly parallel 55 with each other, all the couplings will be released, because of the rollers u turning away from the segmental ribs on the casting o . The wings b and c then are also turned about an angle of 90° out of the position shown in Fig. 2, from whence they can easily be completely turned outwardly by the people rushing 60 out. It will be clearly gathered from the above description and from the drawing that, whenever the door-wings pass the position, in which the wings stand at right an-

gle to and parallel with the direction of the 65 central vertical plane of the door a change of the coupling pieces takes place, those having been in engagement being now released by their rollers running off from their ribs, while the rollers of other coupling pieces mount 70 some other ribs. Each wing carries similar arms and coupling pieces, therefore, the door will always be acted upon in the same manner described above, no matter in which position the door during its normal rotation is 75 arrested; the coupling mechanisms always acting in such manner that the inner wings which are first met by the people trying to rush out, may be turned about their rods f in the direction of the arrows I and IV, while 80 the outer wings are acted upon by the first to turn in the direction of the arrows II, III.

As has been said before the door-wing taking the position of the wing c , will be coupled to its driving arm 5^c by a coupling having 85 play or idle motion. For this reason the arm 5 of each wing is provided with two coupling pieces one above the other, one with and the other without play. The coupling piece having no play is arranged in the 90 level of the rib w^a and the other having play in the level of the rib w^c , Fig. 1.

Instead of making use of the coupling mechanism shown in Fig. 1 and 2 and more particularly in Fig. 3 and 4, other coupling 95 mechanisms may be made use of, for instance such as is shown in Fig. 5. This coupling mechanism consists of a double armed lever l^1 fulcrumed at l^2 in a slot l^3 of the boss of arms named above or their substitutes. A 100 coupling stud m^1 is pivoted to the lower arm of this lever and engages in an opening of the socket e . On the other side of its pivot the coupling stud m^1 is provided with a beveled nose m^2 . A similar nose n^2 is arranged on a 105 second stud n^1 pivotally attached to the other arm of lever l^1 . The latter stud, which only serves as a guiding-stud is of such length that when it is withdrawn or completely enters the slot, it cannot touch the socket e , while the coupling stud m^1 , is so much longer that in its retracted position it engages a notch or 110 slot in the socket e to a sufficient extent to secure the coupling between the boss and the socket. The lever l^1 is so shaped or so arranged that the nose of the guiding stud n^1 115 projects out from the boss, when the nose of the coupling stud m^1 is in its retracted position. In order to throw the couplings into or out of engagement, instead of segmental 120 ribs merely tongues p attached to some fixed part project into the path of the noses m^1 and n^1 . These tongues p are situated, where in the first modification the ribs start, thus changing the position of the coupling- 125 pieces on the same place. Instead of providing the sockets e with bosses carrying arms, other means such as chains and sprockets and the

like, may be employed for operatively connecting the shafts to compel the wings to jointly swing outward. When in normal use of the door the four wings must be locked together at their inner ends. This may be done by any desired locking mechanism, that is released when the people rush out to open the wings.

The locking mechanism shown in drawings Figs. 7 and 8 consist of a drop-weight *y*, which carries four noses *z* engaging correspondingly shaped notches at the lower corners of the door-wings. On the weight *y* there is a square plate 10 rotatively connected by a central stud or bolt 11. The corners 12 of this plate project into apertures 13 on the inner ends of the door wings, when in locked position, thus holding the weight *y* in the position shown. The size of the square plate is some what less than the square space between the ends of the door-wings, when in working position. When the plate is turned about the pivot stud 11 for 45° it loses its grasp on the bottom of the apertures 13 and the weight *y* drops down, thus retracting the noses *z* from their engagement with the doorwings and releasing them. The rotation of the plate 10 is carried into effect by means of a pawl 14 attached to a vertical rod 15, of which there is one in each door-wing. In the level of about the usual door-handles there is an arm 16 attached to the rod 15, that can be turned by means of an outwardly arranged handle 17, which may extend nearly across the whole breadth of the door. For the sake of better appearance a similar handle 18 is arranged on the other side of the door, which however is not turnable but is attached in fixed position and may merely serve to rotate the complete door when in normal use. The turnable handle 17 is situated on that side of each door wing, which is in the back of the people walking through the door normally, so that as a rule there is no need nor opportunity to touch this handle, which may cause the unlocking of the door-wings when pushed inwardly. When however in case of danger the people rush out blindly, they naturally press against both surfaces that present themselves, therefore are also bound to push the handle 17 inwardly and thus unlock the door-wings.

In the construction shown the handle 17 must overcome a certain power before the unlocking takes place, to prevent this unlocking being carried out unintentionally. For this purpose there is a knuckle-joint connected with the handle, consisting of two arms 16 and 21 telescoping into sockets 24 which are parts of the hinge 23 connected by a pivot pin 25. The arm 16 is attached to the rod 15 spoken of above and the arm 21 pivoted to a stud 22. Two helical springs 19 and 20, of which 19 surrounds the arm 16,

and 20 the arm 21, tends to hold the parts in the position shown in full lines, by pressing against the bosses of the arms 16 and 21 at one end and against the hinge 23 at the other end. The pin 25 of the hinge is arranged to slide in slots 26 of the bifurcated end 27 of the handle 17. When this handle is pressed inwardly also the pin 25 and hinge 23 is moved inwardly, increasing the tension of the springs 19 and 20 and forcing the sockets 24 to slide over the arms 16 and 21 until these parts come in the plane of the pivot 22 and rod 15. As soon as this position is passed the springs 19 and 20 act to move the parts farther on in the same direction which now suddenly jump into the position shown in dotted lines, the pin 25 sliding in the slot 26 of the bifurcated end 27 of the handle 17. A similar locking mechanism is provided for the upper part of the door. The weight *y* however is replaced by a spring 28, attached to a plate having similar noses *z* and also a turnable plate 10; these parts being arranged upside down, the spring 28 has the tendency to pull the locking mechanism upward. The turnable plate may be turned by pawls 14 which are attached to the same rods 15 and are similarly shaped as the lower pawls 14, so that by the inward movement of one of the door handles both locking mechanisms are unlocked and the door wings released. In order to set the locking mechanism in the floor as well as in the ceiling of the door there is an opening, that may be normally closed by a cover 30 or the like. In the floor there may be a lever 29 to lift the weight *y* by hand or foot, and when in this position the plate 10 may be adjusted by a finger, for which an opening may be provided for in one or more door wings. A similar lever 31 is provided for in the ceiling of the door for the same purpose.

The system of arms and links described above may advantageously be furnished with means for re-adjusting such arms and links into working order. These means may consist of springs 32 fixed to the arms at one end and pressing against the rod sidewise at the other end. Thus the springs compel the arms and links to open out, when standing at an acute angle. To prevent this opening out to surpass an angle of 90° the arms are provided with side-arms 33 at their ends, standing at right angles to them. The free ends of the springs are also adapted to press against these side arms, so that, when the arms and links are opened out by the springs, these latter abut against the side arms 33, as soon as the right angle position is attained. Therefore all the arms and links return into their normal position, shown in Fig. 2, as soon as, after opening the door-wings, the coupling-pieces are released, and no readjustment of the system of arms and links by

hand is necessary, when the opened door is reset into working order.

I claim:

1. A revolving door comprising a plurality of wings adapted to revolve about a central axis and means to simultaneously swing said wings away from said axis.
2. A revolving door comprising a plurality of wings detachably connected at one edge and pivoted at their outer edges, and means connecting the pivots to swing the wings conjointly on their outer pivots.
3. A revolving door comprising a plurality of wings detachably connected at their inner edges, a shaft at the outer edge of each wing on which they are pivoted, and means for operatively connecting the shafts to compel the wings to swing conjointly about such shafts.
4. A revolving door comprising a plurality of wings, locking mechanism at the center for detachably connecting the wings, means for pivotally mounting the wings at their outer edges, and means for unlocking said mechanism by pressure against one wing to disconnect all the wings simultaneously.
5. A revolving door comprising a plurality of wings, locking mechanism at the center for detachably connecting the wings, shafts for pivotally mounting the wings at their outer edges, means for unlocking said mechanism arranged to be operated by pressure on the wings, and means for operatively connecting the shafts to compel the wings to swing conjointly outward.
6. A revolving door comprising a plurality of wings, locking mechanism at the center for detachably connecting the wings, shafts for pivotally mounting the wings at their outer edges, means for operatively connecting the shafts to compel the wings to swing conjointly, and mechanism to couple the connecting means to said shafts at certain position of the door wings.
7. A revolving door comprising a plurality of wings detachably connected by locking mechanism at the center, shafts on which the wings are pivoted at their edges, arms pivoted to the shafts, and links connecting the arms of the neighboring shafts.
8. A revolving door comprising a plurality of wings, detachably connected by locking mechanism at their center, shafts on which the wings are pivoted at their outer edges, arms pivoted to the shafts, links connecting the arms of the neighboring shafts, and means to couple the arms to said shafts at certain positions of the wings.
9. A revolving door comprising a plurality of wings detachably connected by locking mechanism at the center, shafts on which the wings are pivoted at their outer edges, arms pivotally mounted on each shaft, a link connecting two of the arms of neighboring shafts, a sliding connection for two other

arms of neighboring shafts, and a coupling mechanism on each arm to couple the same to its shaft at certain positions of the wing.

10. A revolving door comprising a plurality of wings, mechanism for centrally locking the wings, shafts on which the wings are pivoted at their outer edges, arms pivoted on the shafts, links connecting corresponding arms of the neighboring shafts, a coupling piece in connection with each arm, and projections on fixed parts of the door for operating the coupling pieces on the rotation of the door to couple the arms to said shafts at certain positions of the door.

11. A revolving door comprising a plurality of wings, mechanism for centrally locking the wings, shafts on which the wings are pivoted at their outer edges, arms pivoted on the shafts, a link connecting a corresponding arm on a neighboring shaft, a coupling piece arranged on the boss of each shaft, and projecting segmental ribs on fixed parts of the door for operating the coupling piece on the rotation of the door to couple the arms to said shafts at certain positions of the door.

12. A revolving door comprising a plurality of wings, mechanism for detachably locking the wings at the center, shafts on which the wings are pivoted at their outer edges, arms rotatably attached to the shafts, a link connecting each arm to a corresponding arm on a neighboring shaft, coupling mechanism to couple the arms to said shafts at certain positions of the door wing to enable the wings to swing outward conjointly and means to retract the arms into normal position when released from the shafts.

13. A revolving door comprising a plurality of wings, locking mechanism detachably connecting said wings at the center, shafts on which the wings are pivoted at their outer edges, a movable handle attached to and arranged to be pressed toward each wing, and means operated by any one of the handles to release the locking mechanism.

14. In a revolving door, the combination with a plurality of wings, of a central locking member adapted to engage each wing, and means on each door to withdraw the locking member from engagement with all the wings simultaneously.

15. In a revolving door, the combination with a plurality of wings, of a central locking member adapted to engage each wing, a movable handle attached to each wing, and means on each door operated by such handle to withdraw the locking member from engagement with all the wings simultaneously.

16. In a revolving door, the combination with a plurality of notched wings, of a locking member provided with a nose projecting into each notch, a plate rotatively mounted on the locking member adapted to engage apertures in the wings, and means for rotat-

ing the plate to release the locking member from the wings.

17. In a revolving door, the combination with a plurality of wings each having a notch in the corner and an aperture above the notch, a locking-piece having a nose for each notch, a plate rotatively attached to the locking member having corners projecting

into the apertures, a movable handle on each door, a pawl connected with said handle adapted to rotate the plate on the handle being pressed inwardly.

CHARLES HARRY ROECKNER.
